(57) **CLAIM**

The ornamental design for a neurostimulator assembly, as shown and described.

DESCRIPTION

FIG. 1 is a perspective view of a neurostimulator assembly showing our new design;

FIG. 2 is a top view thereof;

FIG. 3 is a bottom view thereof;

FIG. 4 is a right side view thereof;

FIG. 5 is a left side view thereof;

FIG. 6 is a rear view thereof;

FIG. 7 is a front view thereof; and,

FIG. 8 is an exploded perspective view of the components of the neurostimulator assembly which are shown separately for clarity of illustration.

The claimed design is patentable over the references cited.
